UNITED STATES PATENT OFFICE.

JACOB KAUFMANN, OF ELKINS PARK, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

LOOM HARNESS.

Application filed April 20, 1923. Serial No. 633,381.

To all whom it may concern:

Be it known that I, JACOB KAUFMANN, a citizen of the United States, residing at Elkins Park, in the county of Montgomery and State of Pennsylvania, have invented certain new and useful Improvements in Loom Harness, of which the following is a specification.

My invention relates to loom harness, and it relates more particularly to the construction and arrangement of the heddles in the heddle frames for controlling the warp ends for the purpose of forming successive sheds of the warp during the operation of the loom.

The object of my invention is to provide an improved form of construction and arrangement of the heddles in the heddle frames which is particularly adaptable for close installations for weaving fine fabrics, and whereby the warp ends controlled by adjacent frames will more freely pass the eyes of the heddles during the reciprocation of the frames for the purpose of forming the sheds, thereby minimizing, to a large extent, breakage of the warp ends.

While it should be understood that the underlying principles of my present invention may be used in connection with various types of heddles, the invention will, however, find its greatest usefulness in connection with that type of metallic heddles as distinguished from cotton or thread harness, which are formed from thin flat strips of metal or wire, having the warp eyes formed in the central portions thereof by slitting the metal of the strip and expanding the same to form the eye through which the warp end passes.

Heretofore, it has been recognized by those skilled in the art that a great deal of breakage of the warp ends occurs by reason of the resistance which occurs during the reciprocation of the various heddle frames in the loom, at the particular instant when the threads controlled by one of the frames passes the warp eyes of the heddles mounted in another of the heddle frames, this occurring particularly in the weaving of fine fabrics where the installation of the heddles in the frames is close, and where the warp is necessarily fine, and therefore more easily broken.

To overcome the above mentioned diffi-

culty, in some instances where there were provided a plurality of sets of heddle frames, each set being operated in unison to control one set of the warp ends, which was a more or less clumsy expedient, and which led to the subsequent development of the mounting of a plurality of sets of heddles in a single frame, arranged in a plurality of separated vertical planes. Another expedient subsequently developed comprised the provision of heddles off-set out of the planes of the supporting bars, and arranged with the off-set portions alternately to one side and another, so as to cause the warp eyes to lie in separated vertical planes. These expedients, however, have been found insufficient to fully accomplish the desired purpose, particularly for weaving fine fabrics, and my present invention contemplates a still further advance in the art, as will be hereinafter more fully set forth.

While there is shown and described in the present application one species of my present invention, and the same is herein shown as embodied in various modifications of said species, I have also shown and described in a companion application, filed herewith, another species and the manner of embodying the same in various modifications thereof. It should, however, be understood that my invention is susceptible of embodiment in a variety of other species and modifications thereof, as will be readily apparent to those skilled in the art upon a proper understanding of the underlying principle of my present invention.

The nature and characteristic features of my present invention will be more readily understood from the following description, taken in connection with the accompanying drawings forming part hereof, in which:

Figure 1 is an elevational view of a heddle frame having heddles, constructed and arranged in such manner as to embody the main features of my present invention, mounted therein;

Fig. 2 is a vertical transverse sectional view thereof; and

Figs. 3, 4 and 5 are sectional views, similar to Fig. 2, but each showing a modified form of construction and arrangement of the heddles.

Referring to the drawings, the heddle

frame there shown consists of the top and bottom bars 6, connected at their ends by means of the side strips 7. Extending from end to end of the heddle frame, and arranged 5 near the top and bottom bars 6 in the usual manner, are the heddle bars 8 upon which the heddles are mounted.

Referring now more particularly to Figs. 1 and 2 of the drawings, the heddles which 10 are mounted upon and supported by the bars 8 are provided in two sets, 9 and 10, respectively. The heddles of the set 9 are off-set, as at 11, so as to cause the central portions of said heddles to lie to one side 15 of the vertical plane of the supporting bars 8, while the heddles of the other set 10 are similarly off-set, as at 12, but so as to cause the central portions of those heddles to lie to the other side of the plane of the supporting bars 8. The heddles are provided with warp controlling eyes in the central portions thereof, which warp eyes may be of any preferred conformation.

The relative location of the warp eyes 13 25 of the heddles 9 with respect to the warp eyes 14 of the heddles 10, when the same are mounted in the frame, is, however, important. The warp eyes 13 are longitudinally located in the heddles 9 and the warp eyes 14 30 are longitudinally located in the heddles 10 at such positions, respectively, that all of the warp eyes of the set of heddles 9 will lie in a horizontal plane different from that of the warp eyes 14 of the set of heddles 10.

35 The heddles are mounted upon the supporting bars by first placing thereon a heddle 9 of one set, then a heddle 10 of the other set, then another heddle 9 of the first mentioned set, then another heddle 10 of the other set, and so on throughout the frame.

In the modification of the invention shown 40 in Fig. 3 of the drawings, there are provided three sets of heddles, 15, 16 and 17. The heddles 15 are straight throughout their 45 longitudinal extent, and preferably lie in the vertical plane of the supporting bars 8, while the heddles 16 are off-set, as at 18, to one side of the vertical plane of the heddles 15 and the supporting bars 8, and the 50 heddles 17 are off-set, as at 19, to the other side of the vertical plane of the heddles 15 and the supporting bars 8. The warp eyes 20 of the straight central heddles 15 may be located at or about a central position between the heddles supporting bars 8, and the warp eyes 21 of the heddles 16 are arranged below the horizontal plane of the said warp eyes 20 of the straight heddles 15, while the warp eyes 22 of the heddles 17 are located 55 in a horizontal plane above that of the warp eyes 20 of the straight central heddles 15. In this arrangement, the heddles are preferably mounted upon the supporting bars 8 in a manner somewhat similar to that of the arrangement shown in Figs 1 and 2,

namely, a straight central heddle 15 is first mounted upon the bars, then one of the off-set heddles 16, then one of the off-set heddles 17, then again one of the straight central heddles 15, then one of the off-set heddles 16, followed by one of the off-set heddles 17, and so on throughout the frame.

The arrangement shown in Fig. 4 of the drawings is somewhat similar to that shown in Fig. 3, with the exception that in this 75 instance the warp eyes 21 and 22 of the off-set heddles 16 and 17, respectively, are both located in a horizontal plane below the plane of the warp eyes 20 of the straight central heddles 15.

In Fig. 5 of the drawings, there is shown another embodiment of the invention, wherein the use of off-set heddles may be dispensed with. In this instance, there are provided, at the top and bottom, respectively, of the frame, two or more of the heddle supporting bars 8, and the heddles in this instance may be substantially straight throughout their longitudinal extent, there being provided one set of heddles 23 which 90 are mounted on one pair of the supporting bars 8, and another set of heddles 24 which are mounted on another pair of supporting bars 8. The warp eyes 25 of the heddles 23 are in this instance located in a horizontal 95 plane different from that of the warp eyes 26 of the other set of heddles 24.

It will be seen that in each of the foregoing arrangements there is provided, in a single harness frame, a plurality of sets of heddles, the warp controlling eye portions of which not only lie in separated vertical planes, but the respective eyes of each set of heddles also lie in separated horizontal planes, and, by this arrangement, as the 100 frames are reciprocated during the operation of the loom, a greater freedom for the passage of the warp ends, controlled by the adjacent frames, will be afforded, in that the warp eyes being located in a plurality 105 of different horizontal planes, resistance to the passage of the warp ends, which are controlled by the other frames, will be greatly minimized, and in this manner breakage of the warp ends, due to the strain which ordinarily occurs at this point, will be reduced 110 to a minimum.

It should also be understood that the various forms illustrated are, to a certain extent, suggestive merely, and that a variety 115 of other forms or embodiments of the invention will readily occur to those skilled in the art.

Having thus described the nature and characteristic features of my invention, what 120 I claim as new and desire to secure by Letters Patent, is:

1. In a loom harness, a harness frame heddle supporting bars carried thereby, and individual heddles mounted upon said sup- 125

porting bars having warp controlling eyes located in their central portions, the warp controlling eyes of one set of said heddles being located in one vertical and one horizontal plane and the warp controlling eyes of another set being located in another and different vertical plane and in another and different horizontal plane, and all of the warp controlling eyes arranged in the same vertical plane being also arranged in the same horizontal plane.

2. In a loom harness, a harness frame, heddle supporting bars carried thereby, and heddles formed of thin flat metal or wire mounted upon said supporting bars having warp controlling eyes located in their central portions, the warp controlling eyes of one of said said heddles being arranged in one vertical and one horizontal plane and the warp controlling eyes of another set being located in another and different vertical plane and in another and different horizontal plane, and all of the warp controlling eyes arranged in the same vertical plane being also arranged in the same horizontal plane.

3. In a loom harness, a harness frame, heddle supporting bars carried thereby, and individual heddles mounted upon said supporting bars and having warp controlling eyes located in their central portions, the warp controlling eyes of one set of said heddles being located in one vertical and one horizontal plane, and the warp controlling eyes of another set being located in a different vertical plane and in a different horizontal plane, all of the warp controlling eyes arranged in the same vertical plane being also arranged in the same horizontal plane, and the heddles being arranged upon the supporting bars in successive series of one of each set.

4. In a loom harness, a harness frame heddle supporting bars carried thereby, and heddles formed of thin flat metal or wire mounted upon said supporting bars and having warp controlling eyes located in their central portions, the warp controlling eyes of one set of said heddles being located in one vertical and one horizontal plane, and the warp controlling eyes of another set being located in a different vertical plane and in a different horizontal plane, all of the warp controlling eyes arranged in the same vertical plane being also arranged in the same horizontal plane, and the heddles being arranged upon the supporting bars in successive series of one of each set.

5. In a loom harness, a harness frame, heddle supporting bars carried thereby, and individual heddles mounted upon said supporting bars and having warp controlling eyes located in their central portions, the central portions of one set of said heddles being off-set to one side of the vertical plane 60 of the supporting bars and the central por- 65

tions of another set being off-set to the other side of said vertical plane of said supporting bars, the warp controlling eyes of one set of said heddles being located in one vertical and one horizontal plane, and the warp controlling eyes of another set being located in a different vertical plane and in a different horizontal plane, and all of the warp controlling eyes arranged in the same vertical plane being also arranged in the same horizontal plane.

6. In a loom harness, a harness frame, heddles supporting bars carried thereby, and heddles formed of thin flat metal or wire mounted upon said supporting bars and having warp controlling eyes located in their central portions, the central portions of one set of said heddles being off-set to one side of the vertical plane of the supporting bars and the central portions of another set being off-set to the other side of said vertical plane of said supporting bars, the warp controlling eyes of one set of said heddles being located in one vertical and one horizontal plane, and the warp controlling eyes of another set being located in a different vertical plane and in a different horizontal plane, and all of the warp controlling eyes arranged in the same vertical plane being also arranged in the same horizontal plane. 95

7. In a loom harness, a harness frame, heddle supporting bars carried thereby, and individual heddles mounted upon said supporting bars and having warp controlling eyes located in their central portions, the central portions of one set of said heddles being off-set to one side of the vertical plane of the supporting bars and the central portions of another set being off-set to the other side of said vertical plane of said supporting bars, the warp controlling eyes of one set of said heddles being located in one vertical and one horizontal plane, and the warp controlling eyes of another set being located in a different vertical plane and in a different horizontal plane, all of the warp controlling eyes arranged in the same vertical plane being also arranged in the same horizontal plane, and the heddles being arranged upon the supporting bars in successive series of one of each set. 115

8. In a loom harness, a harness frame, heddle supporting bars carried thereby, and heddles formed of thin flat metal or wire mounted upon said supporting bars and having warp controlling eyes located in their central portions, the central portions of one set of said heddles being off-set to one side of the vertical plane of the supporting bars and the central portions of another set being off-set to the other side of said vertical plane of said supporting bars, the warp controlling eyes of one set of said heddles being located in one vertical and one horizontal plane, and the warp controlling eyes 120
125
130
135

of another set being located in a different vertical plane and in a different horizontal plane, all of the warp controlling eyes arranged in the same vertical plane being also arranged in the same horizontal plane, and the heddles being arranged upon the supporting bars in successive series of one of each set.

9. In a loom harness, a harness frame, 10 heddle supporting bars carried thereby, and heddles mounted upon said supporting bars in a plurality of sets having warp controlling eyes located in their central portions, the central portions of one set of said heddles being arranged in the vertical plane of the supporting bars, the central portions of another set of said heddles being off-set to one side of the vertical plane of said supporting bars, and the central portions of an 15 other set being off-set to the other side of said vertical plane of said supporting bars, the warp controlling eyes of one set of said heddles being arranged in one horizontal plane and the warp controlling eyes of another set being located in another horizontal plane.

10. In a loom harness, a harness frame, heddle supporting bars carried thereby, and heddles formed of thin flat metal or wire 30 mounted upon said supporting bars in a plurality of sets having warp controlling eyes located in their central portions, the central portions of one set of said heddles being arranged in the vertical plane of the supporting bars, the central portions of another set of said heddles being off-set to one side of the vertical plane of said supporting bars, and the central portions of another set being off-set to the other side of said vertical plane of said supporting bars, the warp controlling eyes of one set of said heddles being arranged in one horizontal plane and the warp controlling eyes of another set being located in another horizontal plane. 35

40

11. In a loom harness, a harness frame, 45 heddle supporting bars carried thereby, and heddles mounted upon said supporting bars in a plurality of sets having warp controlling eyes located in their central portions, the central portions of one set of said heddles being arranged in the vertical plane of the supporting bars, the central portions of another set of said heddles being off-set to one side of the vertical plane of said supporting bars, and the central portions of 50 another set being off-set to the other side of said vertical plane of said supporting bars, the warp controlling eyes of one set of said heddles being arranged in one horizontal plane and the warp controlling eyes of another set being located in another horizontal plane, and the heddles being arranged 55 upon the supporting bars in successive series of one of each set.

12. In a loom harness, a harness frame, 60 heddle supporting bars carried thereby, and heddles formed of thin flat metal or wire mounted upon said supporting bars in a plurality of sets having warp controlling eyes located in their central portions, the 65 central portions of one set of said heddles being arranged in the vertical plane of the supporting bars, the central portions of another set of said heddles being off-set to one side of the vertical plane of said supporting bars, and the central portions of another set being off-set to the other side of said vertical plane of said supporting bars, the warp controlling eyes of one set of said heddles being arranged in one horizontal 70 plane and the warp controlling eyes of another set being located in another horizontal plane, and the heddles being arranged 75 upon the supporting bars in successive series of one of each set.

In testimony whereof, I have hereunto signed my name.

JACOB KAUFMANN.
